UNITED STATES PATENT OFFICE.

ADDI BENJAMIN CADMAN, OF BELOIT, WISCONSIN, ASSIGNOR TO WARNER MANUFACTURING COMPANY, OF BELOIT, WISCONSIN, A CORPORATION OF WISCONSIN.

BOLSTER AND CHOCK.

1,411,403.

Specification of Letters Patent. Patented Apr. 4, 1922.

Application filed May 24, 1920. Serial No. 383,653.

To all whom it may concern:

Be it known that I, ADDI BENJAMIN CADMAN, a citizen of the United States, residing at Beloit, in the county of Rock and State of 5 Wisconsin, have invented certain new and useful Improvements in Bolsters and Chocks, of which the following is a specification.

My invention relates to equipment for the 10 transportation of logs and similar articles and more specifically to an improved bolster and bolster chock for trucks.

One of the objects of my invention is to provide a bolster and a chock which are of 15 simple construction, cheap to manufacture and durable in service.

Another object is to provide a bolster and a chock so constructed that the chock may be mounted on the upper side of the bolster 20 to retain a load thereon, or may be suspended below the bolster to serve as a support for a loading skid.

Another object is to so arrange the parts 25 of the chock that the various devices associated therewith may be attached or removed without interfering with each other. Further objects and advantages of my invention will become apparent as the description proceeds.

30 My invention in its preferred form comprises a bolster having outwardly extending flanges on the upper and lower surfaces, and a chock detachably mountable upon either surface of the bolster and embodying means for receiving and holding a stake, means for attaching a so-called booming chain for binding the load, and means for securing a locking chain to prevent escape of the chock from the bolster.

40 In loading pipe, logs or similar articles from the ground it is customary to use skids, usually pipes or pieces of timber, inclined from the ground with their upper ends resting on the bolsters. Difficulty has been experienced in suitably supporting the skids 45 on the bolsters at a level which would deliver the logs directly to the carrying surface of the bolsters. By reversing the chock and suspending it from the lower side of the 50 bolster I am able to provide a convenient and stable support for the upper end of such a skid.

55 In the devices of the prior art, the booming chain and the locking chain have usually been attached to the chock in such a manner

that the booming chain gets in the way of the fid hook and the locking chain so that the latter cannot be released. My invention avoids this difficulty by reason of the novel shape and relationship of the parts of 60 the chock.

In the accompanying drawings I have shown a preferred embodiment of my invention, in which Fig. 1 is a perspective view of a bolster mounted on a truck or trailer body carrying at each end a chock in position for retaining the load. Fig. 2 shows one of the chocks in reversed position for supporting the end of a skid. Fig. 3 represents a plan view of one end of the bolster 70 with a chock mounted upon its upper side. Fig. 4 represents an end view of a typical load supported on a bolster and chocks, with a partial view of the mounting attachments carried by a truck. Fig. 5 illustrates the 75 general method of loading logs and the like upon a combination vehicle comprising tractor and trailer trucks.

The bolster selected for illustration comprises two channels 10 laid back to back and 80 united into a rigid frame by small channel sections 11, one at each end, and a central block 12 to which the channels are suitably secured as by rivets.

The outwardly extending flanges of the 85 channels form the support for the chocks on the upper and lower surfaces of the bolster. The block 12 has a simple socket 13 to receive a king-pin (not shown) for the pivotal mounting of the bolster. The bolster 90 may be supported upon a truck platform 14 by means of a bed 15 suitably attached to the platform as by bolted straps 16 and centrally carrying a fixed plate 17 on which the king pin is mounted. Suitable shoes 18 may be 95 provided to slidably support the ends of the bolster.

The chock illustrated, indicated in its entirety by the reference character 19, has suitable means supporting it slidably on the 100 upper and lower surfaces of the bolster. This means consists of laterally extending wings 20 having reversely bent portions 21 engaging the flanges of the channels 10. Locking chains 22 attached at their inner 105 ends to the mid portion of the bolster extend out and through a laterally opening tubular passageway or barrel in the side boss 23 of each chock. Each locking chain carries at its end a suitable fid hook 24 which may be 110

hooked over the link of the chain at the end of the passageway whereby the chock is locked against outward movement, in any desired position along the upper surface of the 5 bolster.

The chock has a simple body comprising walls 25 rising from the wings 20, the inner edges of the walls extending at an angle and being reinforced by a web portion 26.

- 10 A notch 26^a for receiving and supporting a loading skid, is formed by the walls and web portion 26. A boss 27, extending out from the body over the wing on the side opposite to the boss 23, is adapted to receive a 15 stake 28 in a suitable socket. The eye 29 for receiving the booming chain comprises a U-shaped portion extending outwardly from the outerside of the body having its upper arm a continuation of the upper surface of 20 the body and being reinforced by a suitable rib 30 lying in a vertical plane and extending over the upper surface of the body and vertically down across the body of the U-shaped portion. Referring to Fig. 4, it will be seen that a booming chain 36 may be attached through the eye 29 and suitably fastened without interfering with the locking chain 22 and fid hook 24 which latter lies at the corner of one of the wings completely out 30 of the way.

Referring to Fig. 5, I have illustrated a manner of loading logs and the like, according to my invention, upon a combination of vehicles comprising a tractor and a trailer.

- 35 The rear portion of a four wheel motor truck is represented at 32, having a bolster 10 mounted as described upon its platform. A trailer truck 33 is shown connected to the motor truck by a suitable draw bar 33^a, and 40 having a bolster 10 mounted upon its frame. A chock 19 is mounted in reverse position on the underside of each of the two bolsters. The skids 31 are shown with their upper ends resting on the chocks and their lower ends on 45 the ground in such position that the log or pipe 34 may be rolled up the inclined skids and rested upon the bolsters in loaded position 35.

The adaptability of the chock in the loading operation, illustrated in Fig. 5, is apparent. When mounted on the under side of the bolster, as illustrated in Fig. 2, it furnishes a positive support upon a portion of the chock extending outwardly from the bolster for the skid 31 which is held in position with its upper end flush with the upper surface of the bolster. With the chocks and skids so arranged on the bolsters mounted on both tractor and trailer it is apparent 55 that heavy logs or pipes may be rolled into position on the bolsters with the greatest facility.

This application is a continuation in part of my prior application, Serial No. 317,962 filed Aug. 16th, 1919.

While I have shown and described in detail a particular embodiment of my invention associated with a specific form of bolster, it should be clearly understood that the description is only for purposes of illustration, 70 that devices according to my invention may be designed to be mounted on other types of bolsters or other supports, and that many other modifications and variations will naturally occur to those skilled in the art. 75 I aim in the subjoined claims to cover all such legitimate variations and modifications.

I claim as my invention:

1. A chock having, in combination, a body, wings projecting from either side of 80 said body adapted to overlie and be supported upon a support, a stake socket portion overlying one of said wings, and a chain receiving portion overlying the other of said wings.

2. A chock having, in combination, a body, wings projecting from either side of said body formed to overlie and be supported upon a support, a stake socket portion overlying one of said wings, a chain receiving portion overlying the other of said wings, and a chain attachment portion projecting outwardly from said body.

3. A chock having, in combination, a body, wings projecting from either side of said body, said wings overlying and supported upon a support, a chain receiving portion overlying one of said wings, and a chain attachment portion projecting outwardly from said body.

4. A chock having, in combination, a body having an inclined inner face and a vertical outer face, a U-shaped eye projecting from said outer face and a reinforcing rib arising from the upper surface of said body and partially embracing said U-shaped eye.

5. In a device of the class described, in combination, a bolster, a chock slidably mounted on said bolster, a locking chain 110 attached at its inner end to a fixed support, and an outwardly and laterally inclined socket in said chock adapted to receive said locking chain.

6. In a device of the class described, a 115 body, wings extending laterally from the lower portion of said body and adapted to rest on a support, attachment means overlying each of said wings, and other attachment means projecting outwardly from said body.

7. In a device of the class described, in combination, a chock, a locking chain attached at its inner end to a fixed support, an outwardly and laterally inclined socket 125 in said chock, said locking chain passing through said socket, and a fid hook attached to the end of said locking chain adapted to lock the chain against withdrawal through said socket.

8. In a device of the class described, in combination, a bolster, two chocks slidably mounted outwardly from the center of said bolster, each cock having outwardly extending means for attaching a booming chain and having means spaced laterally therefrom to secure a locking chain, said means being arranged to prevent interference between said booming chain and locking chain.
9. In a device of the class described, in combination, a bolster and a chock, said bolster and chock having interengaging means for mounting said chock selectively on top of said bolster to serve as load retaining means or underneath said bolster to serve as skid supporting means.
10. In combination with a supporting bolster, a chock having slidable means of selective attachment to the upper side or under side of said bolster or either end thereof.
11. In combination with a supporting bolster, a chock slidably mounted on the underside of said bolster having a portion extending outwardly therefrom to support a loading skid.
12. In combination with a supporting bolster, a chock mounted on the underside thereof adapted to support a loading skid.
13. In a device of the class described in combination, a vehicle body, a bolster mounted thereon having symmetrical ends extending outwardly from said body, and a chock movably mounted on said bolster having means of attachment thereto arranged to permit placing said chock in position selectively above or below either end of said bolster.
14. In combination with a supporting bolster, a chock mounted thereon comprising a body portion, wings projecting from either side of said body portion adapted to engage said bolster in slidable attachment selectively upon its upper or under surfaces on either end thereof, a stake socket portion carried by one of said wings, a chain receiving portion carried by the other of said wings, and a chain attachment portion extending outwardly from said body.
15. In combination with a supporting bolster, a chock mounted thereon by slidable means of attachment adapted to engage said bolster selectively upon its upper or under surfaces at either end, an outwardly and laterally inclined barrel through said chock, a locking chain in fixed attachment at its inner end with said bolster and passing through said barrel, and means for locking said chain against withdrawal through said barrel.

In testimony whereof, I have hereunto set my hand.

ADDI BENJAMIN CADMAN.
